UNITED STATES PATENT OFFICE.

ANDREW J. CURRY, OF ST. LOUIS, MISSOURI.

DESIGN FOR A HAT-RACK.

SPECIFICATION forming part of Design No. 30,121, dated January 31, 1899.

Application filed January 3, 1899. Serial No. 701,052. Term of patent 14 years.

To all whom it may concern:

Be it known that I, ANDREW J. CURRY, of the city of St. Louis, State of Missouri, have invented a new and original Design for a Hat-Rack, of which the following is a full, clear, and exact description, reference being had to the accompanying drawings, forming a part hereof.

Figure 1 is a plan view of a hat-rack, showing my new design. Fig. 2 is a side elevation thereof.

As shown in the drawings, the leading or material feature of my design consists of a rectangular frame 1, there being vertically-arranged corner-posts 2 at each corner of said frame, and transversely arranged upon top of the frame are the parallel ribs 3. Appearing on top of said ribs 3 are small lugs 4, from which extend upwardly and inwardly

curved arms 5, the same sustaining the oval rings 6. Crossed slits 7 are formed in the material that covers the center of the frame or body, which crossed slits are arranged immediately beneath each of the oval rings 6. The curved arms 5 and the rings 6 sustained thereby are arranged in pairs upon the ribs 3, and said ribs and rings are also arranged in parallel lines extending longitudinally upon the body or frame 1.

I claim—

The design for a hat-rack, substantially as herein shown and described.

In testimony whereof I affix my signature in presence of two witnesses.

ANDREW J. CURRY.

Witnesses:

EDWARD E. LONGAN,
ALBERT J. McCUALEY.
